UNITED STATES PATENT OFFICE.

LEROY P. CLUTTER, OF BEAVER FALLS, PENNSYLVANIA.

EXCAVATOR.

1,405,288.

Specification of Letters Patent. Patented Jan. 31, 1922.

Application filed August 15, 1914. Serial No. 856,989.

To all whom it may concern:

Be it known that I, LEROY P. CLUTTER, a citizen of the United States of America, residing at Beaver Falls, in the county of Beaver and State of Pennsylvania, have invented certain new and useful Improvements in Excavators, of which the following is a specification, reference being had therein to the accompanying drawing.

10 This invention relates to improvements in excavators.

Among the objects of my invention are the following:

(1) To provide a device of this character which may be readily applied to an ordinary type of motor such as a portable or traction steam engine.

(2) To provide a device of this character having a traveling excavating bucket controllable by a single operator without affecting the operation of the motor.

(3) To provide a device adapted for pivotal movement on a vertical axis and having a beam pivoted on a horizontal axis to form a way for a traveling excavating bucket, the beam and the bucket being controllably moved through independent connections from a single shaft.

(4) To provide a device of this character in which the movements of the excavating bucket and the beam on which it travels are controllable independently of each other and from approximately the same point, also to provide means for moving the beam and its bucket bodily on a pivotal axis, with the operating mechanism for providing such movements in fixed position.

(5) To provide improvements of the support for the excavating bucket whereby the bucket may be positionable in parallelism with or angularly to the direction of length of the support for the bucket.

(6) To provide an improved excavating bucket adapted to permit of a dumping of the material at will.

(7) To provide an improved mechanism for steadyng the device, said mechanism being movable into and out of an operative position without removal from the apparatus.

Other objects are to provide a device of this character which is composed mainly of metallic beams of ordinary cross-sectional configuration, to provide a built-up structure

of exceeding strength and of few parts, all arranged compactly and of a strength adapted to withstand rough usage and the strains to which a device which is simple and efficient in operation, durable in construction, readily repaired, and which can be manufactured and installed at a relatively low cost.

To these, and other ends, the nature of which will be readily understood as my invention is hereinafter disclosed, said invention consists in the improved construction and combination of parts hereinafter fully described, illustrated in the accompanying drawings, and particularly pointed out in the appended claim.

In the accompanying drawings, in which similar reference characters indicate similar parts in each of the views:—

Figure 1 is a view in side elevation of my device applied to the front of a portable engine, the excavator bucket and its supporting beams being shown as slightly raised.

Figure 2 is a front elevation of the same with the bucket and the supporting frame shown as swung to one side, the supporting beam being shown in substantially horizontal position.

Figure 3 is a view in side elevation similar to Figure 1, with the bucket carrying beam raised and omitting the side support for the device.

Figure 4 is a detail view in elevation of a portion of the steadyng device.

Figure 5 is a plan view of the structure shown in Figure 4.

Figure 6 is a transverse sectional view of the construction shown in Fig. 5, showing the dog engaging the side bar.

The present invention designed more particularly as an attachment capable of being placed in position at the front or other convenient point of a suitable motor, preferably of a portable or traction steam engine type, the engine frame forming a support for two metallic beams 20 of any desired cross-sectional configuration and which extend longitudinally of the frame, as indicated in Figure 1, being secured to the frame work of the motor in any desired manner. The forward ends of the beams are connected together by cross-beam 21 which not only serves as a connecting and bracing

member for said beams but also as a carrier for the pintle member 22 of a pivotal connection presently described, said pintle being positioned approximately midway of 5 the distance between said beams, but spaced therefrom so as to place the pintle in advance of the cross-beam 21.

Secured to the beams 20 and extending vertically therefrom and spaced from the 10 front ends thereof are vertical uprights 23 which are connected together at their upper ends by a suitable brace 24, these parts forming the rear frame of the apparatus.

Extending vertically from said beams 20 15 at a point adjacent the front ends of said beams are two-part uprights 25, each of said uprights extending in two vertical planes substantially parallel but spaced apart, the lower part of these uprights extending in a plane inside of the plane of 20 the upper part, as indicated in Figure 2, said parts being connected together by suitable plates or other connections 26, the structure being such as to provide a front 25 frame for the apparatus, the lower part of which frame is of a length between the upright portions less than the length between the upper portions of the uprights.

Said uprights of the front frame are also 30 connected at their tops by a brace 27. The two frames are connected by brace 28.

Rising vertically in the plane of the front frame and intermediate the upright members forming said frame, are two spaced- 35 apart bars or members 30 which are secured to the top and bottom braces of said frame. Secured to the front of said bars or members adjacent the top brace 27 is one of the members of a top pivotal connection 31, 40 presently described, the pintles of the top connection 31 and pintle member 22 having their axes substantially in vertical alignment in order that the swinging portion of the apparatus presently described may be 45 swung on a substantially vertical axis. This axis corresponds to the axis of a circular member 32 positioned at the top of the apparatus and which is adapted to provide the turning movements of the shiftable portion 50 of the apparatus.

The shiftable portion of the apparatus is connected to the frame work above described by means of the complementary members of the pivotal connections referred to, 55 said complementary members being carried by a vertical upright 33 suitably formed, but preferably comprising two metallic bars spaced apart with the hinge members extending therebetween and secured in such 60 position. The upper end of the upright 33 is provided with a horizontal member 34 to the top surface of which the circular member 32 is secured, said member 34 projecting forwardly beyond said circular member and having its forward end secured 65

to an inclined beam or member 35 inclined to the vertical and having its lower end secured to the lower end of the upright 33, and shown in Figs. 1, 2 and 3 of the drawings said beam 35 being also preferably formed 70 of metallic beams spaced apart, in order to provide strength with lightness. The upper end of said beam or member 35 carries the sheave or pulley 36 over which one of the pull ropes or cables hereinafter referred 75 to passes, the structure being such that said beam 35 retains its position relative to the vertical upright 33, regardless of the pivotal movements of the shifting apparatus.

Pivots secured at the lower end of the 80 upright 33 is the supporting beam or carrier 37 for the excavating bucket, said beam consisting principally of a metallic beam preferably composed of two spaced-apart members secured together, the lower flanges of 85 said beam forming a run-way on which the bucket travels. The outer end of said beam is provided with a sheave or pulley 38 over which the pull rope or cable for the movements of the bucket passes. Said front end 90 is also provided with a suitable member such as an eye 39, to which the outer end of the pull rope or cable for controlling the movements of the beam 37 is secured in a suitable manner.

The parts heretofore described comprise the main portion of the frame work of both the stationary and the shiftable portions of the derrick. As will be readily understood, the shiftable portion is so formed as to permit of a swinging or pivotal movement bodily on the upper and lower pivotal connections 22 and 31, while the supporting beam 37 may be raised or lowered on its pivot while at the same time provision is made for 105 moving the bucket lengthwise of said beam, these being all of the movements of the swinging portion of a derrick required to perform the desired work, and the construction is such that the parts are of a maximum strength without an increase in weight of material, while all of the parts are so braced as to withstand all strains, etc., to which they may be subjected in the operation 110 of the apparatus.

The excavating bucket, is designated as 40, consists of a bottom 41, pivotally connected with the forward end of a wall, rising vertically from the plane of the bottom when in closed position the said wall extends 115 around substantially three sides of the periphery of the bottom, leaving the front open, the opposite sides being preferably inclined, as shown. The outer face of the wall and the periphery of the bottom being in substantially the same plane to provide a structure in which the bottom lies against the under edge of the wall. The bottom is provided at its front with a plurality of teeth or fingers 43, which are adapted to act in ad- 120 125 130

vance of the front edge of the bottom in loosening the material being operated upon. It will be understood that the material taken up by the bottom in the movements of the 5 bucket will be carried backward into the interior of the bucket, as the latter is given its forward movement in operation, the bracket being shown in general in Figs. 1 and 2 with its supporting and operating mechanism and 10 fully described in detail and claimed in Patent No. 1,107,899 granted to me on August 18, 1914.

For the purpose of providing the various movements to the shiftable portion of the 15 derrick I preferably provide the following: 57 designates a shaft extending laterally across the stationary frame and preferably in juxtaposition to the front upright frame, which shaft is provided with a drive pulley 20 58 connected to the motor in a suitable manner. The shaft 57 extends entirely across the frame and is provided with a pair of clutch elements, cooperating with complementary members 61, 62 loosely mounted on 25 the shaft, each of said members being in the form of a circular web having a flared periphery or apron, said apron normally overlying its cooperating clutch elements. The members 61 and 62 are loosely mounted on 30 35 the shaft 57 and are adapted to be coupled together by movements axially of the shaft.

Power devices are associated with the clutch elements 61 and 62 and comprises a shaft 67 forming the drive shaft and on 40 which a sprocket wheel 68 is mounted and connected to the member 61 or 62, as the case may be. Said shaft is also provided with a pinion 69 adapted to engage with a gear 70 mounted on a shaft 71 carrying a 45 winding drum 72 upon which the rope or cable is adapted to be wound or unwound.

Secured to the upright 25, at a point adjacent its top, are two plates 94, the lower ends of which are bolted to two spaced-apart bars 95 and to a brace member 96 50 extending laterally across and projecting outside of the uprights 25, the plates 94 and brace member 96 providing a stiff frame or support for the bars 95, each of which is 55 provided with spaced-apart openings 97 to permit of adjustment in the position of the bars relative to the said frame. Adjacent to the lower ends the bars 95 are connected together in spaced-apart relation by suitable straps 98. On the opposite edge of said bars, each is provided with inwardly extending projecting portions 99 which, in connection with the straps 98, complete a 60 slideway for an adjustable member or bar 65 100 having its lower end pivotally connected to a plate 101 preferably having its corners bent downwardly, as shown in Figures 4 and 5. At a suitable point in the length of said bar 100, I preferably provide a plurality of ratchet teeth indicated at 102, which are

adapted to be engaged by either one of two pawls 103 mounted on a pin 104 carried in brackets 105 positioned on the bars 95, said pawls being of different length so as to permit of adjustment of the bar 100 in the direction of length of the bars 95 in relatively small distances without the necessity of a large number of ratchet teeth, thereby enabling of the formation of teeth of sufficient size to retain the parts in adjusted position. The plate 101 is also pivotally connected to a brace 106 which has its rear end pivotally connected to the stationary frame of the apparatus, said brace being formed in two parts in the nature of a toggle device, 75 one of the parts being of relatively short length.

In use, the parts are arranged as shown in full lines in Figure 2, with the plate 101 in contact with the ground, the brace 106 having its parts in alignment, by manipulating the pawls 103, the proper adjustment as to length between the ground and the upper end of the steadyng device is secured with sufficiently close accuracy as to prevent lateral swaying of the apparatus in use. When it is desired to release the steadyng device, it is necessary to release the engagement between the active pawl 103 and the rack formed by the ratchet teeth 102, whereupon 90 the bar 100 may be moved longitudinally of the bars 95 to the position shown in dotted lines in Figure 2, the brace 106 being formed of pivotal sections as shown to permit it to assume the position shown in said dotted 95 lines. This latter position removes the steadyng device to an out of the way position. As these devices are duplicated on opposite sides of the apparatus, it will be readily understood that the apparatus is 100 firmly held against lateral swaying or substantial vibratory movement and by reason of its presence, provides an apparatus structure relatively light and of a minimum weight.

This particular structure is especially adapted for use in connection with apparatus being used where the ground is not hard and where there is a tendency of the apparatus to sink. In such case the swinging of the beam 37 laterally has the effect of causing a pressure to be placed on the side to which the beam is being swung. When this action takes place, if the surface of the ground on which the plate 101 rests is not sufficiently hard to sustain such pressure, the plate will tend to sink under this pressure and upon the return movement of the beam, which has the effect of releasing a portion of this pressure, the upper portion 115 of the apparatus will tend to draw the outer casing provided by the members 25 upwardly relatively to the bar 100 thereby permitting a pawl to engage a different notch and thus automatically take up for any sag- 120 125 130

ging or sinking of the plate in use, so that in operation any tendency of the apparatus to rock due to the sinking of the plates will be corrected and practically eliminated by 5 the successive operations of the beam in this respect, thus eliminating any requirement for the use of jacks or any similar mechanism for the purpose of retaining the parts steady.

10 While I have herein presented and described a preferred form for carrying my invention into effect, I am aware that changes and modifications therein may be made and may be found necessary to suit 15 the various exigencies of use, and I reserve the right to claim any and all such changes and modifications as may be found necessary and advisable, so long as such changes and modifications fall within the spirit and 20 scope of the invention as expressed in the appended claim.

Having thus described my invention, what I claim as new is:—

Automatic positioning means for excavators comprising a frame adjacent the top of the excavator, spaced bars adjustably carried obliquely by the said frame, ground-engaging means slidably carried between the said bars freely movable in a downward direction, automatic return preventing means for the said ground-engaging means, and a folding toggle brace connection pivoted between the said engaging means and the excavator adapted for unfolding during the automatic operation of the device. 35

In testimony whereof I affix my signature in the presence of two witnesses.

LEROY P. CLUTTER.
